UNITED STATES PATENT OFFICE

SARAH SKREE WEFAULD, OF HAWLEY, MINNESOTA

IRONING STAND

Application filed April 16, 1929. Serial No. 355,592.

This invention relates to the class of laundry and pertains particularly to an improved type of ironing stand.

The primary object of the present invention is to provide an ironing stand which may be easily and conveniently set up for use and which has associated therewith means whereby the user may hang up articles after ironing the same without moving 10 from ironing position.

Another object of the invention is to provide an ironing stand so supported that the user may sit while ironing and thus avoid usual extreme fatigue which accompanies 15 this operation.

The invention broadly contemplates the provision of a board and a pair of end supporting frames, each of which frames carries a hanger designed to receive one end of 20 the board, the hanger being provided with upstanding pins which are adapted to engage in suitable recesses formed in the under face of the board adjacent the end thereof, the end of the board being suitably reinforced to prevent the pins pulling from position. Connecting the lower ends of the frames with the side edges of the board are brace members, the connections between the ends of the braces and the board and the 25 frame being pivotal so that the frames may be readily swung to position under the board when it is desired to fold the same up for storing.

Each of the frames in addition to the foregoing has an upstanding portion which is provided with supporting bars upon which ironed clothes may be hung after drying.

The invention will be best understood 30 from a consideration of the following detailed description taken in connection with the accompanying drawings forming a part of the present invention with the understanding, however, that the invention is not confined to any strict conformity with the showing of the drawings but may be changed or modified so long as such changes or modifications mark no material departure from the salient features of the invention as expressed in the appended claims.

In the drawings:—

Figure 1 is a perspective view of the ironing stand embodying this invention;

Figure 2 is a plan view of the under face of one end of the ironing board;

Figure 3 is a sectional view through a portion of one end of the board and supporting structure therefor;

Figure 4 is a detailed perspective view of one hanger for an end of the board;

Figure 5 is a perspective view of the ironing stand partially folded;

Figure 6 is a detailed perspective view of one end of the ironing board of the stand;

Figure 7 is a section taken on line 7—7 of Figure 6.

Figure 8 is a view in side elevation of the folded stand.

Referring to the drawings in detail wherein like numerals of reference indicate corresponding parts throughout the several views, the numeral 1 indicates the body of the ironing board embodying the present invention, the same being of suitable length and width, as shown and arranged against the under face of the board along each edge is a reinforcing metal frame 2 which carries along each side, a side plate 3 between which plates the board 1 loosely positions. The frame 2 is removable so that the board 20 may be covered with a suitable ironing cloth which, when the frame is replaced, is clamped in place by the frame.

The transverse end bars 4 of the frame and the under face of the board adjacent thereto have recesses or holes 5 formed therein for the reception of holding pins hereinafter described.

For the support of each end of the ironing board body there is provided a frame 30 comprising a pair of leg members, each of which is indicated by the numeral 6, these legs being connected at their upper ends by a plurality of spaced parallel bars 7 which also serve in the set-up board as clothes supports, the portions of the legs carrying these bars extending a substantial distance above the set-up board as will be hereinafter described.

Connecting the legs of each pair at a

point below the bars 7 is a hanger frame 8 which consists of a back plate 9 and a bottom plate 10 which is secured at one edge along the lower edge of the back plate and which is connected at each end with the back plate by the end walls 11. Any suitable means may be employed for securing the ends of these hanger members to the legs between which they position. The bottom plate 10 of each hanger member carries a plurality of upstanding pins or pegs 12 the number thereof corresponding to the number of apertures 5 formed in the under face of the ironing board body at the ends thereof.

Extending downwardly from the central portion of each hanger 8 is a pair of brace bars 13 which are arranged in downwardly diverging relation and are each secured at their lower ends to a leg member adjacent the lower end of the same.

Detachably and pivotally connected at the point 14 adjacent the lower end of each leg is one end of a side brace member 15, the other end of the member being offset inwardly as at 16 designed to be pivotally and detachably secured to a side edge of the ironing board body 1, preferably at the inner end of the reinforcing bar 4 by a thumb screw 17.

Each of the side plates 3 carries a pair of eyes 18 adjacent each end and each of the legs 6 carries upon its outer face adjacent its upper end a hook 19 and upon its inner face just above the hanger 8 a second hook 20. When the ironing stand is set up, each of the hooks 20 engages one of the eyes 18 of the frame side plate 3 adjacent thereto and thus assists the pins 12 in maintaining the stand in set up position.

When the stand is folded, as shown in Figure 8, it is preferable that the pair of legs at one end thereof, after disengagement of the hooks 20 and the removal of the pins 12 from the apertures in the end of the board, be swung to a position under the board while the other frame may be swung outwardly and upwardly to a position parallel with and resting upon the top of the board. With the legs disposed in this manner, the hooks 19 of each will then be in position for engagement with one of eyes 18 and the structure will then be securely maintained in folded condition. It will be readily seen that by providing the offset end portion 16 each of the braces 15 will be permitted to freely swing past the eyes 18.

From the foregoing description it will be readily seen that when the ironing board embodying the present invention is to be set up for use, the leg frames are first arranged in substantially upright position so as to receive upon the hangers 8, the ends of the board 1, the pins 12 entering the apertures 5 in the board as the board is lowered

onto the hanger. This lowering of the board onto the hangers 8 with the resilient downward pressure against the brace bars 15 forces the legs 6 to upright position and when the ends of the board are secured on the pins and in the hangers 8 it will be seen that the clothes bars 7 will be arranged in a plane above the board so that as the board is being used the clothes being ironed thereon may be hung on these bars after the ironing operation is completed.

Having thus described my invention, what I claim is:—

1. An ironing board structure, comprising a board body provided with apertures in one face adjacent each end, a support for each end of the board comprising a pair of legs and a hanger connected between the legs of each pair, each of said hangers comprising a back plate and an angularly extending bottom plate, and pin members carried by the bottom plate of each hanger for engagement in the apertures in one end of the board.

2. An ironing board structure, comprising a board body provided with apertures in one face adjacent each end, a support for each end of the board comprising a pair of legs and a hanger connected between the legs of each pair, each of said hangers comprising a back plate and an angularly extending bottom plate, pin members carried by the bottom plate of each hanger for engagement in the apertures in one end of the board, and brace elements each pivotally connecting a leg member at a point adjacent the lower end with a side edge of the board inwardly of the end thereof.

3. An ironing board structure, comprising a board body provided with apertures in one face adjacent each end, a support for each end of the board comprising a pair of legs and a hanger connecting between the legs of each pair, each of said hangers comprising a back plate and an angularly extending bottom plate, pin members carried by the bottom plate of each hanger for engagement in the apertures in one end of the board, connecting bars between the legs of each pair above the hanger member thereof, brace elements each pivotally connecting a leg member at a point adjacent the lower end with a side edge of the board inwardly of the end thereof, and fastening elements designed for securing each end support of the board in place when the same is folded against one face of the board.

4. An ironing board structure, comprising a board body, a reinforcing frame designed to receive said body and abutting the underface along each edge thereof, and having apertures in its end members, a support for each end of the board comprising a pair of legs, a hanger structure carried by each pair of legs for the reception of an end of the

board, elements carried by each hanger designed to detachably engage the apertures in one end of the board, and brace bars connecting the lower portion of each support at each side with an adjacent side of the board.

5 In testimony whereof I hereunto affix my signature.

SARAH SKREE WEFALD.
